Primary Examiner—Terry A. Wallace*Assistant Examiner*—R. Barkai*Attorney, Agent, or Firm*—Kelly, Bauersfeld & Lowry[57] **CLAIM**

The ornamental design for a skate chassis, as shown and described.

DESCRIPTION

FIG. 1 is a bottom, front and right side perspective view of a skate chassis embodying my new design;

FIG. 2 is a right side elevational view thereof;

FIG. 3 is a bottom plan elevational view thereof;

FIG. 4 is a top plan elevational view thereof;

FIG. 5 is a left side elevational view thereof;

FIG. 6 is a front elevational view thereof; and,

FIG. 7 is a rear elevational view thereof.

The phantom line sketches of the skate boot, wheels and brake shown in the drawings are for illustrative purposes only and form no portion of the invention.
